ADJUSTABLE WORK-PIECE SUPPORT

Guthrie B. Stone, Honeoye, N.Y., assignor to Stone
Conveyor Company, Inc., Honeoye, N.Y.

Continuation of design application Ser. No. D-749, Jan.
24, 1966. This application Dec. 22, 1966, Ser. No.
5,154

Term of patent 14 years

(Cl. D55—1)

FIGURE 1 is a perspective view of an adjustable work-piece support showing two legs omitted and one fragmentarily depicted for ease of illustration; and

FIGURE 2 is an end view with the legs broken away for convenience of illustration.

This is a continuation of design application Ser. No. D-749, filed Jan. 24, 1966 and now abandoned.

Having thus described my invention, I claim:

The ornamental design for an adjustable work-piece support, substantially as shown and described.
